UNITED STATES PATENT OFFICE.

ADOLF ALEXANDER KARL NOWAK, OF BOUS-ON-THE-SAAR, GERMANY.

ROLLING-MILL.

1,013,429.

Specification of Letters Patent.

Patented Jan. 2, 1912.

Application filed March 26, 1910. Serial No. 551,714.

To all whom it may concern:

Be it known that I, ADOLF ALEXANDER KARL NOWAK, a subject of the Emperor of Austria-Hungary, and residing at Bous-on-the-Saar, Germany, have invented a certain new and useful Improvement in Rolling-Mills; and I hereby declare the following to be a full, clear, and exact description of the invention.

20 In rolling mills employing planetary shaping rolls, it is now customary to use either cam shaped rolls, that is, the working face of each roll is eccentric to its axis, or axially mounted rolls with annular working faces. These latter rolls are sometimes mounted in sliding bearings so that the rotation of the disk or carrier in which the bearings slide, is reinforced in effect by the centrifugal force imparted to the rolls thereby. 25 In mills of this type the stationary guides which limit the outward travel of the forming rolls are straight and lie parallel to the axis of the blank so that the rollers held against this guide by centrifugal force, follow it through the working portion of their travel, and during this travel smooth out the wales that are formed when the roll first strikes the blank. Mills of this character are more properly denoted hammering mills 30 than rolling mills, since the rolls strike the blank with a hammer stroke. The superiority of a true rolling mill over a mill of this type is acknowledged since the resiliency of the metal of the blank is much more 35 permanently overcome by the steady pressure of the shaping rolls than by the hammer blows of the rolls of the mill mentioned.

The present apparatus comprises a rolling mill in which the planetary working 40 rolls are circular and are mounted on their true axes in movable bearings in combination with guides arranged to engage said axes or bearings during the working portion of the travel of each roll and press said 45 rolls against the blank in a predetermined pressure curve. The shaping of the blank is thus determined by the curvature of the guide and not by blows imparted through rolls the strokes of which are determined by 50 the centrifugal force imparted thereto.

Guides for pressure rolls are admittedly old in reciprocating progressive rolling mills of the "step by step" type where roller groups are mounted in a reciprocating 55 frame. But obviously these mills are of a distinct type, and furthermore a special

guide for each roller is provided, on which the roller runs back and forward. This type of mill is quite distinct from the present in which the rolls are planetary and each roll of the group is governed during its working travel by the common guide.

In the accompanying drawings several embodiments of the invention are illustrated.

Figures 1 to 3 inclusive are vertical sections showing a roller group at different stages of its revolution; Fig. 4 is a side elevation of the same showing the guides; Fig. 5 is a vertical section at right angles thereto; Figs. 6, 7 and 8 are side elevations showing different methods of adjusting the guides; Fig. 9 is a diagrammatic side elevation of a modified form of the invention in which the rolls are mounted on chains; and Fig. 10 is a similar view of another modified arrangement in which but a single group of rolls is employed.

Turning to the embodiment of my invention shown in Figs. 1 to 5, this arrangement shows the shaping rollers *b* mounted on spindles *c* extending between the flanges *a²* of the carriers *a*. The spindles *c* are radially displaceable, and may be, as shown, held against rotation by pins *g* on which they slide. Springs *g¹* on the pins bear against the spindles and tend to force the latter radially inward. Guideways *d* against which the spindles *c* bear during the working travel of the rollers are located on the inner face of the frame *a¹* and may be made integral therewith, as shown in Fig. 5. This guideway *d* is of course shaped for the particular work in hand, and preferably in such manner that the working roll during the first portion of its working travel (Figs. 1 to 2) stretches the blank, on the mandrel *f* for example, and then (Figs. 2 to 3) smoothes it into shape. The guide *d* is thus graded to effect the desired action of the working roll. After the attack of each roll 100 the blank is advanced slightly together with the mandrel *f* and is preferably rotated through an angle of 90°, for instance by a handle *f¹* clamped on the mandrel *f* as shown in Fig. 1. The blank and mandrel 105 may be advanced at different speeds, if desired, so that the blank will either be drawn on or be pushed off of the mandrel. The advance and rotation of the blank is accomplished principally in the intervals between 110 the working attacks of the rolls.

In order to shape the tube (in the ex-

ample shown) to different thicknesses or in order that the same guide may be employed in shaping tubes of different sizes, the guide may be made adjustable as shown for example in Figs. 6, 7 and 8. In Fig. 6 one end of the guide is pivoted to the frame a^1 and the other end connected to the lever h , through the nut h^1 on the end of which passes the screw h^2 . In Fig. 7 the guide is shown provided with slots through which bolts pass by means of which it may be secured in desired position. In Fig. 8 the working face of the guide is made removable so that any desired shape may be secured in position. This form has the further advantage that the working face is renewable in case of wear, without replacing the entire guide. Again this working face may be made of harder metal than may be necessary for the body of the guide.

Obviously it is not essential that the working rollers be supported in a carrier of the disk type shown in Figs. 1 to 5. Thus in Fig. 9 they are mounted upon a chain i passing over driving chain wheels a^2 . As long as a section of the blank as desired may thus be subjected to the working of the rolls and the pressure guide d^2 is correspondingly lengthened. Two series of oppositely faced rolls are likewise unnecessary, since the one may be replaced by a stationary form k (Fig. 10) with which the rolls b coöperate.

I claim—

1. A rolling mill having a group of displaceable shaping rolls and a rotary carrier having bearings therefor, in combination with a common roll guide carried directly by the frame and arranged between the axis of said carrier and the roll bearings so as to come into effective engagement with said rolls consecutively during the working travel of each roll and force it outward, substantially as described.

2. A rolling mill having a group of displaceable shaping rolls and a rotary carrier having bearings therefor, in combination with a common adjustable roll guide carried directly by the frame and arranged between the axis of said carrier and the roll bearings so as to come into effective engagement with said rolls consecutively during the working

travel of each roll and force it outward, substantially as described.

3. A rolling mill having a group of displaceable shaping rolls and a rotary carrier having bearings therefor, in combination with a common adjustable roll guide carried directly by the frame and arranged between the axis of said carrier and the roll bearings so as to come into effective engagement with said rolls consecutively during the working travel of each roll and force it outward, a lever connected to the guide, a nut on the end of the lever and a screw, which passes through the nut, substantially as described.

4. A rolling mill having a group of displaceable shaping rolls and a rotary carrier having bearings therefor, in combination with a common roll guide carried directly by the frame and arranged between the axis of said carrier and the roll bearings so as to come into effective engagement with said rolls consecutively during the working travel of each roll and force it outward and means in connection with said guide for altering the working travel of said rolls.

5. A rolling mill having a group of displaceable shaping rolls and a rotary carrier therefor in combination with a common roll guide mounted directly on the frame between the roll bearings and the axis of the carrier, and bearings on said rolls adapted to engage said guide during their working travel, substantially as described.

6. A rolling mill having a group of displaceable shaping rolls and a rotary carrier therefor in combination with a common guide for said rolls arranged between the latter and the axis of the carrier, and bearings on said rolls adapted to engage said guide during their working travel, together with resilient means to hold said rolls against said guides, substantially as described.

In testimony whereof I have signed my name to this specification, in the presence of two subscribing witnesses.

ADOLF ALEXANDER KARL NOWAK.
